Application March 19, 1937, Serial No. 131,898
 In Great Britain April 14, 1936

23 Claims. (Cl. 101—27)

This invention relates to marking machines and is herein illustrated with reference to a machine of the type adapted for use in making identification marks upon articles of apparel, although it is to be understood that the invention may have application in connection with the marking of any article.

One type of machine for this purpose commonly includes a work support and a marking head which are relatively movable toward each other to press a marking strip, extending between the support and head and having marking medium on its side adjacent to the work support, into engagement with the work whereby the marking medium is transferred from the strip to the work in a configuration conforming to that of the characters on the marking head. Usually, although not necessarily, the marking head comprises a heated die which may be in the form of an engraved plate or a plurality of interchangeable type which may be reset whenever it is desired to change the mark.

It is a general object of the present invention to provide an improved machine of the type referred to above which affords better visibility and accessibility to the work support and marking head than has been attained in prior machines. To this end, the marking strip in the illustrated machine is normally supported so as to extend at a substantial inclination diverging from the work support toward the front thereof but is adapted to be carried by a movable guide into proximity to the work support before the strip is engaged by the marking head. Thus a relatively wide gap exists between the marking strip and the work support at the time when the work-piece is placed on the support without impairing the effectiveness of the marking head because the above-mentioned guide is operated to move the marking strip into engagement with the work piece which is substantially parallel to the marking head before the latter engages the strip so that all portions of the characters on the marking head will be brought to bear with equal pressures on the marking strip and for the same length of time.

Resetting of the type pieces in the marking head of the illustrated machine is facilitated by moving the marking head into a type-resetting position well above the guide such that the type are gravitationally held in the head, and in accordance with another feature of the invention the marking strip and the holder upon which the forward end of the marking strip is stored are lowered, simultaneously with the above-men-

tioned movement of the marking head, to a position below the type-resetting position of the head so that the visibility of the marking head is not obscured by any of the mechanism normally in front of it and also so that there will be no interference with the changing of type in the marking head.

The invention also contemplates the provision of means actuated by movement of the marking head into its type-resetting position for preventing the marking head from being unintentionally operated toward and away from the work support before the head has been returned to its starting position after a type-resetting operation.

These and other features of the invention will be apparent from the following detailed description read in connection with the accompanying drawings and will be pointed out in the claims.

Fig. 1 is a side elevation of an illustrative machine in which the invention is embodied;

Fig. 2 is an elevation of the side of the machine opposite to that shown in Fig. 1;

Fig. 3 is a fragmentary side elevation of the front portion of the machine illustrating the marking head in its type resetting position;

Fig. 4 is a front elevation of the mechanism illustrated in Fig. 3;

Fig. 5 is a sectional view of latching means for holding the marking head in the type-resetting position, the section being taken along the line V—V in Fig. 2; and

Fig. 6 is a sectional view of a portion of a marking strip feeding mechanism, the section being indicated by the line VI—VI in Fig. 2.

The illustrated machine comprises a frame (Figs. 1 and 2) in the forward lower part of which is mounted a work support 12 adapted to support a work-piece against the pressure of a marking head 14 which is arranged to be moved toward the support 12 to press a marking strip 16 having a coating of marking medium thereon against the work in order to impart thereto a printed impression of the characters on the marking head 14. The work support 12 is mounted for movement toward and away from the marking head 14 to accommodate different thicknesses of work and is thus adjusted by turning a hand nut 18 into which is threaded the stem of the work support which extends downwardly into the frame 10. The positioning of the work on the work support 12 is facilitated by spring pins 20 which are arranged to yield downwardly under the influence of the marking head 14 in order not to interfere with its movement. The marking head 14 is removably mounted by means of dovetailed con-

nections 22 in a carrier 24 arranged to receive electric heating elements 26 and mounted on a shaft 28 to swing upwardly and forwardly away from the support 12 into a convenient position, 5 to be termed hereinafter the type-resetting position, to facilitate the changing of the type in the marking head 14, as will be described later. The shaft 28 is fixed to the forward side of a slide 30 mounted for vertical movement in guideways 10 10 32 formed in an extension of the frame 10 overhanging the work support 12. The slide 30 is moved to operate the marking head 14 toward and away from the work support by connections 15 comprising a lever 34 pivoted at 35 to the slide 30 and arranged to rock about a fulcrum 36 at the upper end of a link 37 pivoted at 38 to the frame 10. The lever 34 is operated from a drive shaft 40 (Fig. 1) having an eccentric 42 by a telescoping connecting rod comprising an eccentric 20 strap 44 which surrounds the eccentric 42 and is bored to receive a rod 46 connected by a ball-and-socket joint 48 to the lever. A yielding connection between the rod 46 and the strap 44 is provided by a lever 50 pivoted at 52 on the eccentric strap 42, the lower end of this lever 25 being adapted to bear against the bottom of the shaft 46, a spring 54 being arranged normally to urge the upper end of the lever 50 away from the eccentric strap 44. Upward movement of the rod 30 46 under the influence of the spring 54 is limited by a pin 56 carried by the rod 46 and arranged to abut the upper shoulder of a recess 57 in the eccentric strap 44.

The shaft 40 is intermittently rotated to carry 35 the machine through one complete marking operation by mechanism including a one-revolution clutch of a common type having an operating member 58 which is actuated by a treadle rod 60 to cause the shaft 40 to be rotated first through a 40 half revolution, whereupon a pin 62 is moved axially to engage projections on the driving pulley (not shown) and is then automatically disengaged from the pulley so that if the treadle is held depressed after the marking head 14 has 45 been moved to press the work against the support 12, the marking head is thus held just as long as may be necessary to produce the required mark on the work. The release of the treadle rod 60 causes the reengagement of the clutch and 50 the return of the marking head 14 to its starting position in which it is illustrated in Fig. 1.

The carrier 24 is held in abutting relation with the end of the slide 30 by a spring 64 (Fig. 2) 55 extending between a swivel block 66 pivoted at the forward end of the lever 34 and a collar 68 fixed to a shaft 70, the shaft being pivoted to an arm 72 extending upwardly from the carrier 24. However, in order to prevent excessive heating of the slide 30, the carrier 24 is swung out of abutting 60 relation with the slide toward the end of its upward movement by a projection 74 on the frame 10 which is adapted to engage an extension formed at the rear portion of the carrier 24.

The arm 72 is swung rearwardly by the operator, to move the marking head 14 to the type-resetting position, by means of a knob 76 pivoted at 78 (Fig. 5) to the arm 72 so as to operate a latch 80 adapted to cooperate with a shoulder formed on a block 82 attached to the frame 70 thereby to hold the carrier 24 in its retracted position. The spring 64 tends to resist this movement of the carrier 24 until the line of centers between shaft 28, the pin connecting arm 72 and rod 70 and the pivot pin of the block 66 passes 75 to the left of a line extending between shaft 28

and the pivot pin of the block 66, and thereafter the spring 64 tends to move the carrier into its retracted position. Thus, by grasping the knob 76 and moving it backwardly the marking head 14 may be swung upwardly and forwardly 5 from its starting position over the work support 12 into a position in which the type are in a convenient position to be seen and interchanged by the operator and yet are gravitationally held in the head because of its inverted position.

The marking head 14 is provided with a plurality of slots 84 (Fig. 4) adapted to receive type pieces which are normally held together within the slots by plungers 86 which extend through the sides of the marking head and are normally urged inwardly by means of springs 88 to clamp the type. The plungers 86 may be moved away from the type to unclamp them by means of levers 90 adapted to engage shoulders on the plungers 86 and pivotally connected by screws 92 to the marking head 14. The levers 90 are automatically swung to unclamp the type when the marking head 14 is moved into its type-resetting position by being moved into engagement with wedge projections 94 fixed at the forward ends of arms 96 secured to the front portion of the frame 10. Thus, although the type do not tend to fall out of the marking head 14 in its elevated position, they are free to be removed from the slots 84 and replaced by other type which, for the convenience of the operator, may be kept in a rack 98 fixed to the top of the frame 10 just above the marking head when in its type-resetting position.

The marking head 14 is locked in the carrier 24 by a latch 98 (Fig. 2) mounted to swing on the left-hand end of the shaft 28 and is normally urged into engagement with the base of the marking head 14 by a spring 100 the ends of which are received in holes in the arm 72 and in another arm carrying a handle 102 integral with the latch 98.

Whenever the marking head 14 is swung into its type-resetting position, starting of the machine is prevented by means comprising a cam 104 (Fig. 1) fixed to the right-hand end of the shaft 28 and arranged to engage a roll 106 on one arm of a three-armed lever 108 rotatably mounted at 110 on the frame 10. The lever 108 is thus swung in a counterclockwise direction (Fig. 1) and causes a stop 112 pivoted at 114 to the frame to be swung into the path of an overhanging portion of a member 116 which is pivotally connected to the treadle rod 60 at 118. The upper ends of the lever 108 and stop 112 are connected by a link 120 having a slot 122 adapted to receive a pin 124 fixed to the stud 112 whereby the stop is permitted to remain in its operative position, until removed therefrom by the operator, even though the marking head 14 may have been returned to its starting position.

Provision is made in the illustrated machine for controlling the marking strip 16 so as to prevent the engagement therewith by the marking head 14 as the latter is being moved to the type-resetting position as well as for moving that portion of the strip directly over the work support 12 into proximity to or engagement with the work, and into a position of parallelism with the marking head 14 when in its work engaging position, before the strip is engaged by the head. 70 Rearwardly of the work support 12 the marking strip 16 passes under a roll 126 mounted on a bracket 128 fixed to the frame 10 to hold the strip at such a height as to accommodate any thickness of work likely to be operated upon by 75

the machine. The strip 16 is led forwardly under the roll 126 in a direction inclined upwardly toward the front of the machine at a substantial angle so as not to obstruct the operator's vision of the work on the support 12 and to facilitate positioning of the work on the support against the pins 20. The strip 16 is thus supported in front of the work support 12 and is held away from the marking head 14 by a member which acts both as a guide and guard, this member comprising an arm 130 the upper end of which is slotted to receive a block 132 pivoted to the forward end of the lever 34. The strip 16 at its forward end is stored on a holder in the form of a reel 134 carried by a spindle 136 mounted in the forward end of an arm 138, the arm being mounted to swing downwardly for a purpose to be described below about a pivot 140 on the frame 10. An arcuate plate 142 adapted to be engaged by the strip 16 is fixed to the lower portion of the arm 130 and is provided with a pair of laterally adjustable guides 144 adapted to position the strip laterally of the plate 142 in engagement with the edges of the strip.

When the treadle rod 60 is lowered the arm 130 also is first lowered with respect to the block 132 to bring the portion of the marking strip 16 extending between the plate 142 and the roll 126 into proximity to or engagement with the work 5 and substantially parallel to the marking head 14 and work support 12, thereby to insure uniformity in the application of both heat and pressure to the strip. The arm 130 is thus operated by a lever 146 the forward end of which is slotted to receive a stud 148 carried by the arm 130 and which is fulcrummed at 150 on the upper end of a support 152 fixed to the frame 10. A spring 154 connecting the rearmost end of the lever 146 and the arm 138 is arranged to urge them both toward their uppermost positions. The lever 146 is operated to move the guide plate 142, as described above, by vertical movement of the member 116 which has fixed to its upper end a stud 156 the upper end of which is slotted to receive a pin 158 fixed to the lever 146. As the arm 130 is lowered its mid-portion is gradually moved rearwardly of the machine under the influence of a spring 160 connecting the arm with the lever 146 in order to minimize the tendency of the guide plate 142 to be swung outwardly as the pivot point 148 swings rearwardly of the machine. This inward movement of the arm 130 is controlled and its downward movement is limited by a cam 162 fixed to the frame 10 and having a rearwardly inclined surface terminating in a hooked portion 164 which is engaged by a roll 166 mounted on the arm 130. It will now be apparent that as the arm 130 is lowered the cam 162 permits the arm to swing rearwardly until the roll 166 strikes the hook 164, whereupon the movement of the arm is arrested, the lower edge of the guide plate 142 now being at substantially the level of the work support 12 and cooperating with the roll 126 to hold the strip against the work piece on the support. The above-mentioned movement of the arm 130 and marking strip occurs prior to the movement of the marking head 14 into engagement with the strip so that all of the type characters in the marking head will engage the strip at the same time and will therefore produce a uniform heating effect upon the marking medium carried by the strip.

By moving the treadle rod 60 to operate the arm 130 as described above, the clutch is tripped 75 by the operating member 58, causing the mark-

ing head to be lowered to its marking position. Shortly after the arm 130 has been moved to the bottom of its stroke by the operation of the treadle rod 60, this movement of the arm being limited by the seating of the roll 166 against the hook 164, the downward swinging of the forward end of the lever 34 causes the block 132 to engage the upper end of a spring 167 mounted in a recess in the slotted portion of the arm 130. Thereafter, the spring 167 yields in response to further downward movement of the marking head and holds the roll 166 against the hook 164 until the marking head is retracted.

The changing of type in the marking head 14 is facilitated not only by swinging the carrier 24 into such a position that the head is conveniently located for the purpose in question but also because the guide plate 142 and the reel 134 are moved out of the line of vision to the marking head, as illustrated in Fig. 3, while the head is in the type-resetting position as will now be described. As the carrier 24 is swung forwardly and upwardly in the manner referred to above, the arm 138 is swung downwardly to carry the reel 134 well below the resetting position of the marking head 14 by a link 168 which connects the arm 138 to the lower end of the lever 108. Simultaneously with this movement the arm 130 is swung outwardly, so that the guide plate 142 prevents the marking strip 16 from being engaged by the head 14, by connections comprising a link 170 pivoted to the arm 138 and having a slot in its upper end adapted to receive a stud 172 carried by an arm 174 extending rearwardly from the upper portion of the arm 130.

The marking strip 16 is led rearwardly from the roll 126 (Fig. 2) between a pair of feed rolls 176, 178, the latter of which is rotatably mounted on a shaft 180 fixed to the frame 10 and has a rubber covered periphery against which the strip is yielding held by the roll 176. The roll 176 is rotatably mounted on an arm 182 arranged to pivot on the frame 10 about an axis which is eccentric with respect to the roll 176 so that by swinging the arm 182 rearwardly the roll 176 is moved away from the roll 178 to facilitate inserting a fresh marking strip in the machine. A spring 184 tends to swing the arm 182 so as to hold the strip 16 in engagement with the roll 178 which is operated intermittently once for each actuation of the marking head 14. The mechanism for thus operating the roll 178 comprises a ratchet 186 associated with the roll 178 and a lever 188 in one arm of which is mounted a pawl 190 adapted to engage the ratchet 186. To the other arm of the lever 188 is pivoted a link 192 which is driven from a crank pin 194 (Figs. 2 and 6) extending through a sleeve 195 to which the link 192 is connected, the pin being mounted for adjustment radially with respect to a drum 196 fixed to the end of the shaft 40. The head of the pin 194 is received in a radial slot 198 in the drum 196 and an arcuate slot 200 in a disk 202 rotatably mounted on a screw 203 threaded in the drum. By turning the disk 202 the pin 194 is moved to any desired position of adjustment in the slot 198, in which position the pin is adapted to be clamped by a nut 204 threaded thereon and arranged to bear against the sleeve 195. The strip 16 passes from the rolls 176, 178 under a guard plate 206 fixed by a screw 208 to the frame 10 to a rewinding reel 210 having a disk 212 which is arranged frictionally to engage the periphery of the drum 196. The reel 210 is rotatably mounted on an arm 214 pivoted at 216 to the

frame 10. The reel 210 is rotated by a motor 218 mounted on the frame 10 and having a shaft 220 extending through a sleeve 222 to which the reel 210 is secured.

frame 10 and yieldingly urged by a spring 218 so as to hold the disk 212 against the drum 196, as described above.

The operation of the machine will now be briefly summarized. Upon treadling the machine the rod 60 and the member 116 are lowered, causing the arm 130 also to be lowered by the connections described above so as to move the portion of the strip 16 beneath the marking head 14 10 downwardly toward the work support from its starting position illustrated in Fig. 1. This downward movement of the arm 130 is limited by the cam 162, the hooked end of which, 164, is engaged by the roll 166 when the bottom edge of 15 the guide plate 142 is moved to substantially the level of the work support 12. Following the above described operation of the arm 130, the clutch is tripped to cause the marking head 14 to be moved toward the work support 12 upon which a work 20 piece will have been placed in engagement with the guide pins 20. The marking head 14 is thus moved into engagement with the strip 16 and holds the strip against the work piece as long as the treadle rod 60 is held down. Upon release 25 of the treadle rod 60 the clutch is actuated to cause the return of the marking head 14 to its starting position and also to return of the arm 130 to its uppermost position, as illustrated in Fig. 1, in which it is to be noted that the marking 30 strip 16, although held out of engagement with the marking head 14 by the guide plate 142, is nevertheless inclined upwardly at a substantial angle toward the front of the work support so as to provide good visibility of, and access to, the 35 work support.

When it is desired to interchange the type in the marking head 14, the knob 76 is moved rearwardly until the latch 80 is operatively engaged with the block 82, thereby holding the marking head in the type-resetting position in which it is 40 illustrated in Fig. 3. In this position the head is well above, and hence clearly visible over, the plate 142. Toward the end of this movement of the marking head the levers 90 engage the projections 94 and are moved outwardly to retract the plungers 86 from engagement with the type in the slots 84. The type are thereby unclamped and are free to be removed but are gravitationally held in the head. As the head is swung toward its type-resetting position, the cam 104 actuates the lever 108 to cause the arm 138 to swing downwardly to such an extent that the reel 134 is disposed below the marking head out of the line of the operator's vision thereto. This movement of the arm 138 also causes the arm 130 to swing forwardly so as to prevent the marking head from engaging the strip 16.

Upon swinging the marking head 14 away from the type-resetting position, the type are automatically reclamped as soon as the levers 90 move out of engagement with the projections 94 and then the arms 138 and 130 are returned again to the positions in which they are illustrated in Fig. 1.

Having described our invention, what we claim as new and desire to secure by Letters Patent of the United States, is:

1. In a marking machine, a work support, a marking head arranged to receive type and comprising a heating member adjacent to said type, an operating member mounted for movement toward and away from said support, said marking head being mounted to swing on said operating member about an axis remote from said heating member, a yielding member arranged

normally to hold said marking head in abutting relation with said operating member, and means for swinging said marking head out of abutting relation with said operating member as the latter is moved away from said support whereby the amount of heat transmitted from the marking head to the operating member is reduced when the head and member are removed from the support.

2. In a marking machine, a work support, an operating member mounted for sliding movement toward and away from said support, a guide for said operating member, a marking head mounted on said operating member for movement into and out of abutting engagement with the member, said marking head comprising a heating member, and means for moving said marking head out of abutting relation with said operating member as the latter is moved away from the support thereby preventing overheating of the operating member and binding between the operating member and the guide.

3. In a marking machine, a work support, an operating member mounted for movement toward and away from said support, a marking head arranged to receive type and comprising a carrier mounted for movement into and out of abutting relation with respect to said operating member, and means operated by movement of said operating member away from said support to move said carrier out of abutting relation with said operating member.

4. In a marking machine, a work support, an operating member mounted for movement toward and away from said support, a marking head arranged to receive type and mounted on said member for movement into and out of abutting relation therewith, means mounted and arranged normally to hold said head in abutting relation with said operating member, and means operable as said member is moved away from said support to move said head out of abutting relation with said operating member.

5. In a marking machine, a marking head adapted to receive a plurality of type, clamping means carried by said head and arranged normally to hold the type releasably clamped therein, a clamp controlling member operable to unclamp the type, said marking head being mounted for movement away from its starting position to facilitate the resetting of type, and means co-operating with said controlling member when said head is moved out of its starting position to unclamp the type.

6. In a marking machine, a marking head having type removably mounted therein, said head being mounted for movement into a type-resetting position to facilitate changing the type, type clamping plungers mounted in said head, a lever for operating said plungers, and a member co-operating with said lever when said head is moved into said position to cause said plungers to release the type.

7. In a marking machine, a marking head having type removably mounted thereon, means for heating the type in said marking head, said head being mounted for movement into a type resetting position to facilitate changing the type, type clamping means slidably mounted in said head, a lever mounted on said head for overcoming the resistance to movement of said clamping means, which resistance may be increased when the clamping means is heated by the type, and a member co-operating with said lever when the head is moved into type resetting position to

cause the automatic release of the type by the clamping means.

8. In a marking machine, a marking head adapted to receive type and mounted for movement into a type-resetting position, a holder for a marking strip disposed normally in the line of vision to said head, and means for moving said holder out of the line of vision to said head as the latter is moved into its resetting position.

10 9. In a marking machine, a type head mounted for movement between a starting position and a type-resetting position to facilitate the changing of type, a holder for a strip of marking material adapted to be pressed against the work by said head, and means for moving said holder below said type head as the latter is moved into its resetting position thereby to render said type head accessible for the changing of type.

10 10. In a marking machine, a marking head adapted to receive a plurality of interchangeable type, said marking head being mounted for movement into a type-resetting position, a holder for a marking strip, said strip normally being directed in front of said marking head, and connections operated by movement of said marking head toward its resetting position for lowering said holder and strip below said marking head when in its resetting position.

30 11. In a marking machine, a type head mounted for movement from a starting position into a type-resetting position, a holder for a marking strip, a guide for said strip, and means actuated by movement of said head toward its resetting position for moving said holder and guide into positions out of the line of vision to said head in its resetting position.

40 12. In a marking machine, a type head mounted for movement from a starting position into a type-resetting position to facilitate the changing of type, a holder for a marking strip, a guide, said holder and guide being mounted to swing into positions below the type-resetting position of said head, and connections operated by movement of said head toward its resetting position for operating said guide and holder.

45 13. In a marking machine, a type head having type removably mounted therein, a guide, means for swinging said head into a position above said guide to facilitate the changing of type, a holder for a marking strip disposed normally above said head and mounted to swing below the said position of said head, cam means for operating said holder, and connections actuated by movement of said holder for moving said guide away from said head as said head is moved toward said position.

55 14. In a marking machine, a work support, a marking head, a marking strip disposed between said head and support and inclined away from said support toward the direction from which a work-piece is placed between said support and head, operating means for relatively moving said head and support to press said strip against the work-piece, a guide engaging said strip and movable to carry said strip into proximity to the work-piece, and operator-controlled means constructed and arranged successively to operate said guide and actuate said operating means.

60 15. In a marking machine, a work support, a marking head, means for supporting a marking strip directed between said support and head and inclined away from said support toward the front thereof, a guide arranged to engage said strip and mounted for movement toward said support, means for operating said head to press said strip against a work-piece on said support,

and means for successively moving said guide to carry said strip in proximity to the work-piece on said support and for then actuating said operating means.

65 16. In a marking machine, a work support, a marking head, means for supporting a marking strip extending between said support and head and inclined away from said support toward the front thereof, said means comprising a guide mounted for movement toward and away from said support, operating means for relatively moving said support and head to cause said strip to be pressed against a work piece on said support, connections between said operating means and guide for moving the latter toward said support, and means for limiting the movement of said guide toward said support.

70 17. In a marking machine, a work support, a marking head, means for supporting a marking strip extending between said support and the head and inclined away from said head toward the rear thereof, said means including a guide mounted for movement away from said head to move said strip into a relation of parallelism with said head, means for relatively moving said head and support to press said strip against a work piece on said support, means for operating said guide, and means for limiting the movement of said guide away from said head when said strip and head are parallel to each other.

75 18. In a marking machine, a work support, a marking head, means for supporting a marking strip over said support and inclined away therefrom toward the front thereof, said means including a member mounted and arranged normally to hold said strip away from said head, means for moving said member away from said head to position a portion of said strip over said support parallel to said head, and means for relatively moving said head and support to cause said strip to be pressed against a work piece on said support.

80 19. In a marking machine, a work support, a marking head, means for supporting a marking strip over said support and inclined away therefrom toward the front thereof, said means comprising a member mounted for movement to position a portion of the strip over said support parallel to said head, means for moving said member away from said head, and means including a cam mounted and arranged successively to guide said member as it is moved away from said head and then to limit the movement of said member away from said head when said strip is parallel to said head.

85 20. In a marking machine, a work support, a marking head having type removably mounted therein, operating means constructed and arranged to move said head and support relatively to each other in one direction to apply pressure to a work-piece disposed therebetween, said head being mounted for movement in another direction into a resetting position to facilitate the changing of type therein, and means mounted and arranged to utilize the last-mentioned movement of said head to prevent the actuation of said operating means.

90 21. In a marking machine, a work support, a marking head having interchangeable type therein, operating means constructed and arranged to move said head and support toward each other to apply pressure to a work-piece disposed therebetween, means for moving said head away from said support into a type-resetting position to facilitate the changing of type, an operator-con-

trolled member for actuating said operating means, a stop, and connections between said last-mentioned means and stop mounted and arranged to move the latter into the path of movement of said member when said head is moved into its resetting position thereby to prevent said operating means from being actuated.

22. In a marking machine a work support, a marking head having type removably mounted therein, operating means for moving said head in one direction to press a work-piece on said support thereagainst, means for moving said head in another direction away from said support to facilitate the changing of type, an operator controlled member for actuating said operating means, and means operated by the last-men-

tioned movement of said head to prevent movement of said member.

23. In a marking machine, a work support, a marking head having type removably mounted therein mounted for movement in one direction into a type resetting position, operating means arranged to move said head in another direction to press a work-piece on said support thereagainst, a member for actuating said operating means, a stop, and connections between said head and stop for moving the latter into the path of movement of said member when said head is in its resetting position thereby to prevent said operating means from being actuated.
